UNITED STATES PATENT OFFICE.

THOMAS J. LOVETT, OF CHICAGO, ILLINOIS.

DESIGN FOR A TIRE-BLOCK.

SPECIFICATION forming part of Design No. 28,074, dated December 21, 1897.

Application filed October 11, 1897. Serial No. 654,896. Term of patent 14 years.

To all whom it may concern:

Be it known that I, THOMAS J. LOVETT, a citizen of the United States, residing at Chicago, in the county of Cook and State of Illinois, have invented and produced a new and original Design for Tire-Blocks, of which the following is a specification, reference being had to the accompanying drawing, forming part thereof.

As shown in the drawing, the leading feature of my design consists of a tire-block A with plain sides, a rounded projection *t*, a plain base *s*, and rounded lateral projections *r r* at

opposite ends of the base, the whole presenting in elevation somewhat the outline of the cross-section of an acorn.

Having described my invention, what I claim as new, and desire to secure by Letters Patent, is—

The design for a tire-block, as herein shown and described.

THOMAS J. LOVETT.
